UNITED STATES PATENT OFFICE.

LOUIS H. WALES, OF NEW BRITAIN, CONNECTICUT, ASSIGNOR TO THE RUSSELL & ERWIN MANUFACTURING COMPANY, OF SAME PLACE.

DESIGN FOR A PLATE FOR ATTACHMENT TO DOORS.

SPECIFICATION forming part of Design No. 32,621, dated May 1, 1900.

Application filed April 4, 1900. Serial No. 11,538. Term of patent 3½ years.

To all whom it may concern:

Be it known that I, LOUIS H. WALES, a citizen of the United States, residing at New Britain, in the county of Hartford and State of Connecticut, have invented and produced a new and original Design for Plates for Attachment to Doors, of which the following is a specification, reference being had to the accompanying drawings, forming part thereof.

Figure 1 is a front elevation of a plate for attachment to doors, showing my design. Fig. 2 is a side elevation of the same.

The contour of my plate is a long and narrow oval figure, as shown, having a plane rounded edge 3. Bordering the front of the plate just inside the said rounded edge is a series of circular bead-like ornaments 4. In the central portion there is a raised plane panel 5 of an oval contour, as shown.

On each side of the central panel 5 there is 20 a series of oppositely-arranged conventional flowers 6, and toward the ends scroll branches 7, extending from the said series of flowers and having leaflets and flowers, with a central flower and leaflet 8 between the two series of scroll branches at each end of the plate, all as shown.

Having described my invention, what I claim as new, and desire to secure by Letters Patent, is—

The design for a plate for attachment to doors, as herein shown and described.

LOUIS H. WALES.
